US0D1074700S

(12) **United States Design Patent** (10) Patent No.: **US D1,074,700 S**
Gu (45) Date of Patent: ** May 13, 2025

(54) **DISPLAY SCREEN OR PORTION THEREOF WITH GRAPHICAL USER INTERFACE**

(71) Applicant: **HUAWEI TECHNOLOGIES CO., LTD.**, Guangdong (CN)

(72) Inventor: **Guosheng Gu**, Shenzhen (CN)

(73) Assignee: **HUAWEI TECHNOLOGIES CO., LTD.**, Shenzhen (CN)

(**) Term: **15 Years**

(21) Appl. No.: **29/871,024**

(22) Filed: **Feb. 10, 2023**

(30) **Foreign Application Priority Data**

Aug. 15, 2022 (CN) 202230529551.2

(51) LOC (15) Cl. **14-04**

(52) U.S. Cl.

USPC **D14/485**

(58) **Field of Classification Search**

USPC D14/485-495

See application file for complete search history.

Assistant Examiner — Gary N Chamberlin

(57) **CLAIM**

The ornamental design for a display screen or portion thereof with a graphical user interface, as shown and described.

DESCRIPTION

The single FIGURE is a front view of a display screen or portion thereof with a graphical user interface showing my new design.

The outermost dash-dot broken lines in the drawing illustrate the display screen or portion thereof and form no part of the claimed design. The dotted broken lines in the drawing illustrate portions of the graphical user interface that form no part of the claimed design.

1 Claim, 1 Drawing Sheet
